Andrew Dougherty, of Brooklyn, N. Y.
Whole No. 1455. Letters Patent No. 90, dated July 23, 1861.

The schedule referred to in these Letters Patent and making part of the same.

To all whom it may concern:

Be it known that I, Andrew Dougherty, of Brooklyn, in the County of Kings, and State of New York, have invented or produced a new and original design or combination of colored pictures for the ornamentation of Playing Cards, and that the following is a full clear and exact description of the same, reference being had to the annexed illustrative sheet of playing cards printed upon the principle of my invention.

My invention consists in combining colored faces, (such as are usually found upon the faces of playing cards,) with colored American flag backs.

In the accompanying specimen sheet the faces of the cards extend from the ace to the king inclusive of each suit, the spotted cards being printed in their customary colors and the face cards in five colors and the whole being ornamented with gold. The back of the sheet is printed in colors with American flags as located with reference to the faces on the opposite sides of the sheet that a complete design of colored flags is combined with the face of each separate card. Hence when the sheet is cut up into cards, each card will have upon its back a complete colored design of the American flag.

In order that the colored flag design or picture may be symmetrical, I prefer to make it contain two colored flags reversed, as printed upon the accompanying specimen sheet; but this may be varied if deemed expedient.

The printing in colors of the faces of the cards and of the backs in colors, and the manufacture of the cards, are effected in the usual manner, and form no part of this invention.

What I claim as my invention and desire to secure by Letters Patent, is
A colored flag design for Playing Cards consisting of a combination of colored faces with colored flag backs, as described and represented in the specimen sheet.

In testimony whereof I have hereunto subscribed my name.
